MULTIPLE BLAST

George A. Lyte, Allentown, Pa.

Application April 7, 1948, Serial No. 19,522

6 Claims. (Cl. 175—115)

1

This invention relates to blasting devices and has for its principal object the provision of a portable timer which will permit the use of a series of firing circuits operated successively at regular intervals of time which would be in the range from two thousandths of a second up to perhaps an eighth of a second or more.

A further object of the invention is to provide a method of distributing to a series of firing circuits, each including at least one detonator or firing element, the full current of the power line in a manner to minimize the shock or vibration of the blast together with an improved breaking down of the formation, whether it be rock, ore, soil, etc.

A further object of the invention is to provide a blasting mechanism which will give complete safety and yet can be placed conveniently near the blast and be controlled from a remote point. Other objects of the invention relate particularly to details of construction and are more particularly pointed out in the claims.

In blasting operations, particularly where the material which is blasted is to be used, it is desirable to break down a large portion of a cliff, for example, without injury to the formation but it is also desired that the concussion caused by the blast shall be as small as possible. In the present machine this is obtained by having a number of circuits up to 150 or more, twenty being illustrated, to be fired in rapid succession, following one another with sufficient rapidity so that the burden of one charge is not thrown out of the way of the mass discharged by the next blast. In this way the concussion is reduced to a small fraction of what it otherwise would be and the thud of the explosion is rather a muffled sound than a sharp burst as in previous art. By spacing the several blasts thru a short period of time the waves from one blast modify the waves from the next succeeding blast and rather tend to cancel out the earth vibration.

Previous workers have devised means for firing two circuits consecutively with a brief pause between them but the number of circuits possible with the usual push down blasting machine is limited to two and the purpose of these earlier blasting machines was to make the entire limited output of the machine available for the second shot by breaking the first circuit before closing the second circuit.

In past times I have successfully made multiple blasts with individual detonation initiating agents having different elements. In this way I can give a simple impulse to as many detonators

2

as the electric current will take care of and since the different detonators fire at different times it is possible to obtain some of the advantages secured in the present case. The difficulties are so great, however, that I no longer use this old method. Obviously it was difficult to secure the proper timings and the nuisance of having to select the appropriate detonators was considerable. In the present case all of the detonators are identical and the entire timing is obtained automatically by the machine.

In the drawings:

Figures 1 and 1—A are top plan views of my device with the cover and panel binding posts removed.

Figure 2 is an end view with one side removed.

Figure 3 is a partial vertical section taken on line 3—3 of Figure 1.

Figure 4 is a section on line 4—4 of Figure 1.

Figure 5 is a side elevation of the rack.

Figure 6 is a wiring diagram.

Referring first to Figure 2, for convenience of transportation my device is built into a case 10 much like an elongated tool box, with a leather grip 11, hinges 18, and suitable suitcase catches 19. All of the mechanism shown in Figure 1 is hidden, when the box is open, by the Bakelite panel 15, carrying the twenty individual circuit binding posts 16 and the three main terminals, of which only the common terminal 17 is seen in Figure 2 as this post hides the two power line terminals 80 and 81 aligned with it. In the bottom of the wooden box, I mount a relatively thick plate of aluminum alloy 20 resting on a rubber gasket 21 and held in place in the box by a suitable number of cleats 22 only two of which are illustrated. It is advantageous to secure the metal base plate against lateral movement and for this reason a number of screws such for example as 23 pass from the aluminum alloy plate thru the rubber gasket and into the bottom panel of the box.

Referring now more particularly to Figure 1 the switch mechanism is carried on an assembly block 24 supported from the aluminum base 20 as by a number of spacer posts 25 of insulating material and being secured by bolts such as 26 to secure the desired rigidity. An auxiliary block 21 is mounted in the center of the assembly block 24 and supports a portion of the leaves of the switches. A recess or groove 30 is cut into the assembly block 24 serving as a path for a rack 31 driven by a pinion 28 on the reduction gearing shaft 29 of gearing mounted in box 37 and driven by motor M. The motor and reduction gear may

be purchased as a unit under the name ratio-motor but obviously the sole purpose of the motor is to drive the pinion and therefore any other means such as a spring motor could be substituted with a loss of efficiency to drive the rack.

Except for the necessity of accurate timing, such as is desired here, the rack bar could be pushed in by hand but as indicated if this were done the time required to push it in would vary and this is undesirable. Another important reason for using the motor driven pinion is that if the device were to be operated by hand the mechanism would necessarily have to be removed quite far from the blast because of safety whereas in the present case since the box is rather low and does not turn over under any normal condition the box could be put close to the blast and the operator can be at a very considerable distance from the box as all he needs to do is close the current to the box.

A rather heavy angle piece 32 is secured to the rear edge of the assembly block 24 so that its tip slightly overlies the groove 30 and engages the top of the rack bar so as to hold it in the proper path. A series of leaf springs 33 are mounted side by side at or near the bottom edge of auxiliary block 27 and each has a down turned end 34 projecting in the path of the rack, that is they extend slightly down into the rectangular channel 30. The opposite ends of these springs 33 are integral with or otherwise connected to a transverse portion 35 which receives current as at the point numbered 36 from the terminal post 17 on the Bakelite panel 15 above. The current consequently flows simultaneously to all of the down turned ends 34. Directly above the bank of leaf springs 33 is a series of separate upper switch leaves 38 each having a wire 39 individual to its own particular circuit. As shown there would be twenty of these springs and 20 wires each leading to the binding post 16 of its own individual circuit which latter would contain from one to fifty or more cartridges. These separate circuits are successively energized with a contact time, and a time interval, such as may be found best.

The rack bar 31 in addition to the usual teeth 40 has a smooth upper surface 41 in which is cut a side recess 42 the bottom of this recess merging smoothly as at 43 with a camming prow 44. A stop 45 limits movement of the rack bar for as the rack bar is moved to the left in Figure 1, the stop 45 engages the optional guide bracket 47 on the side of the box. The location of this stop 45 is preferably such that the camming prow 44 of the rack 31 will reach the nearest spring 33 at the time the motor M is revolving at full speed and therefore the rack will be moving at a uniform rate, making the intervals between the firing of successive circuits almost exactly alike.

As the camming prow 44 engages the down-turned end 34 of the first lead spring 33 the latter is raised until contact is made with the down-turned end 49 of the superposed leaf spring 38. This action completes an electric circuit, as will later be explained, to the first one of the firing circuits. A slightly farther movement of the rack bar 31 will permit the down-turned end 34 to lower on the sloping, curved portion 43 of the recess 42 so that as soon as the leaf 33 drops into the recess the current will be shut off from the first circuit and almost immediately thereafter will be delivered to the second circuit. In some of my models I have increased the dis-

tance between the points 43 and 44 at the nose of the rack bar so that the first circuit is not opened until an appreciable time after the first circuit has been energized, however, I desire that this period be extremely brief or omitted entirely because at times the bridge wires of a detonator are short circuited and if two circuits were on for an appreciable time there would be at least a possibility of draining the second circuit because of the short in the first circuit. The rack bar under the urge of the pinion 28, driven by any means desired, continues successively to raise all twenty of the leaf springs 33.

Immediately after engaging the last of the spring fingers 33 the camming prow 44 of the rack bar strikes the multiple contact switch operating lever 50 which like the spring leaves 33 is in the path of the rack bar 41. This lever is secured to a multiple switch shaft 51 mounted in bearings 52. The shaft 51 extends at the right hand side in Figure 1 beyond the bearing to mount an arm 54 constantly urged upward by the spring 55 against a suitable stop 56 which limits downward movement of the point of the lever 50. The shaft 51 carries a member which is called a comb and is numbered 60. This comb could well be a single sheet of metal but I much prefer to cut slots in it as shown at 61 to form individual fingers 62 so that when this comb engages simultaneously all twenty of the leaves 33 each leaf will be pressed definitely and firmly. The object of this movement is to insure that if any one of the twenty firing circuits was not energized at the proper time it will now be energized. While I have never had a failure by any means for the rack to operate all of the circuits I feel that the comb should be used, this being merely a safety measure.

Located between the lever 50 and the bearing 52 at the right there is an important safety element, which is a cut off switch to insure against improper operation. The lower leaf of the switch 64 is numbered 65 and has a projection 66 which can be engaged by corresponding contact element 67 on the upper leaf 68 of this switch 64. The upper leaf 68 projects downwardly as at 69 into the path of the rack bar. As the rack bar passes this point it engages the down-turned end and lifts it slightly so as to separate the contact points 66 and 67. This action shuts off all current to the box and its contents. A slight further movement of the rack bar 31 engages the plunger 70 of a dash pot arrangement consisting of a cylinder 71 containing a spring 72 to cushion the motion of the rack bar and finally to limit it as when the set screw 73 engages the end 74 of the slot in the barrel of the dash pot element.

The switch 64, as previously stated, in addition to being a cut off is a safety device acting as follows: When the rack bar 31 is all the way in and engages the plunger 70 no current is delivered to the device but if an operator should unwittingly try to move the rack bar out (to the left) the upper spring leaf 68 in lowering would establish current to the motor 35. Since the motor revolves in only one direction it would pull the rack bar out of the operator's hands and return it properly into contact with the plunger 70. Consequently there is no possibility of an operator accidentally pulling out the rack bar (with the distant main switch 79 closed) and firing a reset circuit. The distance between the lever 50 and the switch 64 is sufficient to prevent operation of any of the firing circuits be-

fore the motor acts as above. Obviously whenever the current is "off" the rack bar can be pulled out without any difficulty but with the current "on" it is impossible for a firing circuit to be accidentally closed. For convenience in operation the rack bar 31 has a handle 16 pivoted as at 11 so that it can be turned at right angles and be received in a recess 18 in the side of the box so that the entire outer surface of the box is smooth.

It is easy to vary the time of the cycle from contact with one leaf 38 to contact with the next leaf by changing the spacing between the leaves, by changing the width of the leaves, and by selecting a desired speed of movement of the rack in its path. Up to the present moment I have found it most satisfactory when the leaves controlling the individual circuits are $\frac{1}{4}$ " wide and the space between them is $\frac{3}{16}$ ", and the space between the switch 64 and the arm 50 is at least double that figure. The best rack movement is obtained by having a motor with a 10 to 1 ratio and revolving at 172 r. p. m. and driving a pinion with 36 teeth. These figures, however, are purely for illustration and can be varied within wide limits. A very convenient way of arranging for a change in the speed of the rack is by putting shims between the motor base and the aluminum plate 20. By removing as many of these shims as desired we can use a larger pinion with the same setting of the motor and rack. While the rack could be the core of a solenoid, I have not found this arrangement very satisfactory.

Referring now to the wiring diagram Figure 6, the power terminals are numbered 80 and 81 and it is understood that long wires lead from these terminals to a distant point where the operator may close the main switch 79 to operate the blast, the rack 31 at that time being drawn out as far as permitted, by the stop 45. Upon the operator closing the switch 79 current passes from the terminal 81 thru wire 82 to the motor M and by wire 83 to cut off and safety switch 64 which is now closed with contact 67 touching contact 68, the current consequently flowing from the lower leaf 65 thru wire 85 to the other power terminal 80. The terminal 81 is also connected by wire 86 to the common terminal 87 and post 17 of all twenty of the firing circuits, the detonators being numbered 88 in the wiring diagram and only a few being shown, the others of course being identical and each connected as by an individual wire 90 to its own leaf spring 38, the down-turned point 49 of which is engaged by the leaf 33 whenever the latter is raised, the current return being then thru wire 91 switch 64 and wire 85 to terminal 80.

Remembering first that the leaves 33 and 38 have made contact at a previous moment to fire the individual detonators and that the leaf 38 is no longer in contact with 33 then the current thru the comb 60 flows as follows: From power terminal 80 thru wire 85 switch 64 wire 93 shaft 51 to comb 60. As this comb is depressed it engages leaves 38 and the current flows simultaneously thru all twenty of the circuits passing thru wires 90, detonators 88, to the common terminal 87 and back thru the wire 86 to the other power terminal 81.

What I claim is:

1. A multiple hole blasting timer comprising a series of circuit switches, means to engage the switches to close and open each of them consecutively, a power line switch in the path

of said means, a lever mounted in the path of the means between the series of circuit switch springs and the power line switch, and mechanism controlled by said lever for simultaneously closing all of the switches, after all of the circuit switches have been closed consecutively and before the current is shut off by the power line switch.

2. A portable multiple hole blasting timer including a rigid base, a pinion, a motor secured to the base and driving said pinion, a rack bar driven by the pinion and including a cam paw, an assembly block secured to the base, a series of springs mounted on said block and all electrically connected together, a series of leaf springs insulated from the first series to form with the first series an aligned set of switches, individual wires leading from each of the second series of springs, one member of each switch lying in the path of the rack bar so that the two leaves of each switch are successively closed by passage of the rack bar.

3. In an electrically fired multiple hole explosive blast, the art of avoiding the use of consumable delay devices while minimizing the resulting earth vibration and improving the breakage of the formation which comprises: forming spaced blast holes, placing in each of these holes an explosive charge, forming a separate circuit for each of the charges including an electrical ring element in each circuit, imparting suitable electric current successively to each ring element at regular time intervals not in excess of $\frac{1}{3}$ of a second, the spacing of the holes and the time interval between successive firings being such that the burden of any charge detonated still serves as a partial burden on the next succeeding charge as it is fired.

4. The method of claim 3 in which the time interval is within the range five to forty milliseconds, the number of circuits is at least ten and the firing current is from 50 to 600 volts.

5. A multiple hole blasting timer comprising an aligned series of circuit switches, a power switch, a motor-driven means to engage the aligned circuit switches so as to close and open them consecutively, mechanism operated by said means and placed so that after opening and closing all of the aligned switches consecutively, the mechanism will simultaneously and momentarily close all of said circuits, and after the engaging means passes the mechanism which closes and opens all of the circuits simultaneously, the means will next open said power switch thereby shutting off the flow of current to the motor which drives the means.

6. A multiple hole blasting timer comprising an aligned series of circuit switches, means manually movable in one direction and motor-driven in the opposite direction to engage said switches so as to open and close them consecutively, a spring-pressed cut-off and safety switch in the path of said means and engageable by said means near the final end of its motor driven travel to overcome the spring and thus shut off current to the motor, the position of the cut-off switch with reference to the last of the series of aligned switches to be opened and closed being such that when an attempt is made to manually return the means from the final end of its travel toward the initial or starting position of the means, before current is cut off from the timer, the cut-off switch will be free to close, supplying current to the driving motor before the en-

gaging means can re-engage said aligned switches, and thus preventing the means from being moved from its final position as long as the timer itself is connected to the source of power.
